Primary Examiner — Susan Bennett Hattan

Assistant Examiner — Marie Fast Horse

(74) Attorney, Agent, or Firm — Carol N. Green Kaul, Esq.

(57) **CLAIM**

The ornamental design for a portable communication device, as shown and described.

DESCRIPTION

FIG. 1 is a top perspective view of the invention.

FIG. 2 is a bottom perspective view of the invention.

FIG. 3 is a front view of the invention.

FIG. 4 is a rear view of the invention.

FIG. 5 is a right side view of the invention.

FIG. 6 is a top side view of the invention; and,

FIG. 7 is a bottom side view of the invention.

1 Claim, 3 Drawing Sheets(56)
